UNITED STATES PATENT OFFICE.

HENRY J. WIEGAND, OF MILWAUKEE, WISCONSIN, ASSIGNOR TO THE CUTLER-HAMMER MFG. CO., OF MILWAUKEE, WISCONSIN, A CORPORATION OF WISCONSIN.

RESISTANCE UNIT.

1,120,259.

Specification of Letters Patent.

Patented Dec. 8, 1914.

Application filed March 22, 1911. Serial No. 616,273.

To all whom it may concern:

Be it known that I, HENRY J. WIEGAND, a citizen of the United States, residing at Milwaukee, in the county of Milwaukee and 5 State of Wisconsin, have invented new and useful Improvements in Resistance Units, of which the following is a full, clear, concise, and exact description, reference being had to the accompanying drawing, forming 10 a part of this specification.

My invention relates to resistance units.

It is especially suitable for use in connection with electrically heated devices and I shall describe it as applied to this use but 15 it is obviously not so limited and in its various adaptations to practice may assume various other forms and be used in various other relations.

My invention has among its various objects to provide a resistance unit which will directly conduct the heat to the object to be heated, which may be made in various forms for use in different constructions, which will distribute the heat to the places 25 where it is most needed, which will occupy the minimum of space, which is a unitary structure and capable of being removed when desired, which will be rugged and have long life in service, and which at the 30 same time will cost but little to manufacture.

Other objects and advantages of my invention will hereafter appear.

In order to illustrate the principle of my invention, I have in the accompanying views shown several forms which a heating unit constructed in accordance with my invention may assume in practice. My invention is, however, in no wise limited in 40 its use to these specific forms and may assume various other forms and be adapted to various other uses.

Figure 1 shows a top plan view of one form of resistance unit. Fig. 2 shows a sectional view of the same in position in an iron. Fig. 3 shows a sectional view of a unit inclosed in a modified form of casing. Figs. 4 and 5 show modified forms of a heating element.

50 The resistance unit shown in Fig. 1 is adapted to use as a heating element for an electric iron and is provided with a flat

base 1 of suitable insulating material, so shaped as to conform to the inside of an iron. Holes 2 are preferably arranged near 55 the center line of the base to permit bolts hereinafter described to pass through the same. V shaped notches 3 having rounded portions 4 at their inner ends are cut in the curved portions of the periphery of the 60 base 1. These notches may be arranged in any desired relation to each other but in a preferred form the notches on one side of the base are arranged opposite those on the other side. At suitable points on each side 65 of the center line of the iron longitudinally disposed ears 5 are struck up from the base 1. In a preferred form these ears 5 are approximately opposite projections 6 between the notches 3 and are provided with rounded portions 7 at their ends similar to the rounded portions 4 of the notches 3.

A reflex resistance material 8, which may consist of a single length of wire, is laced back and forth transversely of the base in 75 convolutions 9 which extend up one side of the base across the top and down the opposite side. The outer ends of each convolution 9 are looped around the projections 6 while the inner ends are looped around the 80 ears 5, the resistance material passing through the rounded portions 4 and 7. The ends of the resistance material are passed through adjacent perforations 10, near the back of the base 1, and are thus brought 65 close together in order to enable them to be readily connected to a suitable source of current supply.

In order to obtain a proper distribution of the heat supplied to the iron, it is desirable to heat certain portions of the object to be heated to a greater heat than other portions. By my improved construction I am able to increase the heat supplied to these portions by pressing the reflected 90 resistance material more closely together at these points. I have illustrated this in Fig. 1 in which it is to be noted that the reflexed resistance material is pressed close together at the tip and around the curved portions 100 of the periphery of the iron where the greatest heat is required, while the reflexed resistance material near the center and back of the iron is compressed less closely. Obvi-

ously I may increase the heat supplied to any portion of any object to be heated by increasing the closeness of the reflexed material or the convolutions at that point, and 5 I may decrease the heat by increasing the distance between the same.

In order to procure the greatest heating efficiency of a resistance unit, it is highly desirable to convey the heat to the object to be heated by conduction rather than radiation so that the losses of heat by radiation are avoided. A heating element constructed in accordance with my invention is especially efficient in this respect, since due to 10 its compact and unitary construction it is capable of being brought into immediate proximity to the object to be heated so that the heat supplied by the unit can pass by conduction directly to the object to be heated.

In Fig. 2, I have as an example illustrated on an enlarged scale a unit constructed in accordance with my invention in position in a laundry iron. Above the resistance material 8 is placed a sheet of mica or other insulating material 11, similar in shape to the base 1. Below the base 1 is placed a similar sheet of insulating material 12. After the unit has been placed between these sheets it is tightly clamped between the heat retaining plate 13 of the iron and the bottom of the iron 14 by any suitable means, as for instance, taps 15 on threaded bolts 16 which pass through perforations in the retaining plate 13, the base 1, the sheets of insulating material 11 and 12, and engage with the bottom plate of the iron. When the heat retaining plate 13 is forced down upon the sheets of insulation these sheets are compressed upon the resistance material 8, carried by the base 1, and inclose the same hermetically. Due to the thinness of the resistance material and the sheets of insulation which may be used, the heating unit 20 is brought into immediate proximity to the bottom plate of the iron 14, and since the pressure causes the mica to fill the interstices between the reflexed portions of the resistance material loss of heat by radiation 25 is avoided and the heat developed by the resistance material is very directly and therefore very efficiently conducted to the surface to be heated.

In Fig. 3, I have shown, on an enlarged scale, a resistance unit constructed in accordance with my invention inclosed in one form of suitable casing. In this figure the base is shown at 1, the resistance material carried thereby is shown at 8, and the sheets 30 of insulating material above and below the same are shown at 11 and 12 respectively. When so inclosed the unit is placed between thin sheets 17 and 18 of a soft metal, such for instance as copper or aluminum, 35 which is softer than the metal of which

the resistance material 8 is composed, yet sufficiently hard to withstand the working temperature of the iron. These sheets of soft metal are pressed together and as a result of this pressure, portions of 70 the insulating material and the soft metal are forced together between the reflexed resistance material 8 so as to form a unitary, compact and air-tight structure. The portions of the metal sheets directly 75 above and below the resistance material 8 will on account of the hardness of the material 8 not be compressed as will that portion between the wires, but will form slight ridges above the material 8 such as 80 those indicated at 19. The edges of the soft metal sheets may be clamped on each other as shown at 20 in Fig. 3, or may be secured together in any desired fashion, depending upon the circumstances and the use 85 for which the particular element is designed. As a result of pressing this soft metal on both sides of the heating unit, the unit is inclosed hermetically, and when heated is adapted to transmit its heat by 90 conduction directly through the soft metal sheets 17 and 18 to the object to be heated. Further, when a heating unit inclosed in such a soft metal casing is clamped in 95 an iron as shown in Fig. 2, the corrugated surfaces of the soft metal plates 17 and 18 tend to conform to the clamping surfaces, and thus assist in increasing the efficiency 100 of the unit by increasing its ability to conduct the heat directly to the object to be heated.

In Fig. 4 I have shown a modified form of a heating element constructed in accordance with my invention in which the base 1 is annular in form and provided with 105 radially extending convolutions of reflected resistance material 8, the convolutions of the same being looped over projections on the inner and outer peripheries of the base in a similar manner to that described in connection with Fig. 1.

In Fig. 5 I have shown a still further modification of a heating element constructed in accordance with my invention wherein a unit of a circular shape is built up of a 110 series of rectangular shaped units. It is obvious that a heating element of any desired shape may be built up, since units constructed in accordance with my invention may assume any desired shape 115 whether in a single plane or curved, and consequently may be adapted to many and diverse uses.

All of these forms and uses fall within the scope and forethought of my invention, 120 which, although I have described it in this application as applied to several forms of resistance units, is not in any way limited to these specific forms, since these forms have been chosen as but illustrative of the 125

principle of my invention which is itself capable of being adapted to many and diverse forms and uses.

What I claim as new and desire to secure by Letters Patent is as follows:

- 5 1. In a resistance unit, a base having integral peripheral projections thereon lying substantially in the plane of the base, and a resistance material laced in convolutions upon said base and looped over said projections.
- 10 2. In a resistance unit, a base having integral projections formed thereon and ears struck up therefrom, and a resistance material laced in convolutions upon said base and alternately engaging said projections and said ears.
- 15 3. In a resistance unit, a base having integral projections formed thereon and ears struck up therefrom, and a reflexed resistance material laced in convolutions upon said base, the outer ends of the convolutions engaging said projections and the inner ends being looped over said ears.
- 20 4. In a resistance unit, a base having a notched edge and ears struck up from the body portion thereof, and a single length of reflexed resistance material laced in convolutions upon said base, the outer ends of the convolutions passing through the notches in the edge thereof and the inner ends being looped over said ears.
- 25 5. In a resistance unit, a base having projections and ears formed thereon, and a single length of reflexed resistance wire wound in convolutions transversely across said base and looped over the projections and the ears, the portions of the reflexed wire near the edge of the base being pressed closer together than the portions near the center of the base.
- 30 6. In a resistance element, in combination, a sheet of insulation having projections integral therewith, and a reflexed conducting wire having relatively small convolutions and being reflexed in relatively large convolutions on one side of said sheet and engaging the projections thereon to form a substantial unitary unit, said convolutions lying in a single plane and resting flat upon the surface thereof.
- 35 7. In a resistance unit, an insulating base having a notched edge and a plurality of centrally located series of ears struck up from the body portion thereof, and a reflexed resistance material wound in convolutions up one side of said base, across one end of the same and down the opposite side, certain of said convolutions alternately passing through said notches and around said ears.

8. In a resistance unit, a base having a notched edge and a plurality of series of ears struck up from the body portion thereof along the middle of the base, said ears being spaced from each other, and a single length of resistance material alternately passing through said notches and engaging said ears, said resistance material being wound up one side of the base, across the end of the same and down the opposite side and having its ends brought out at one end of the base in close proximity.

9. A resistance comprising a wire mat of a single thickness divided into two substantially longitudinal sections connected only at one end and formed of a continuous reflex wire having relatively small convolutions terminating in close proximity.

10. In a resistance unit, an insulating base, and a reflexed resistance material carried upon one surface thereof and interlocked therewith, said resistance being divided into two substantially longitudinal sections connected only at one end and formed of a continuous reflexed wire having relatively small convolutions terminating in close proximity.

11. In a resistance unit, a base, a resistance material carried thereon, and a soft metal casing inclosing the same and compressed thereon until the metal of the resistance material is partially surrounded by the metal of the metallic casing.

12. In a resistance unit, a base, a resistance material mounted thereon and laced in convolutions thereupon, means for insulating said resistance material, and a soft metal casing inclosing the same and pressed into intimate heat conducting relation with respect to said resistance material and conforming to the convolutions of said resistance material.

13. A resistance unit having a flat base, peripheral projections on said base extending in the plane of said base, attaching means for an electrical conductor arranged on said base and spaced from the periphery thereof, said attaching means being adapted to lie substantially in the plane of the base, an electric resistance element arranged in convolutions on said base and held thereto by being alternately passed over said radial projections and said attaching means.

In witness whereof, I have hereunto subscribed my name in the presence of two witnesses.

HENRY J. WIEGAND.

ALFRED HALVERSON.

Corrections in Letters Patent No. 1,120,259.

It is hereby certified that in Letters Patent No. 1,120,259, granted December 8, 1914, upon the application of Henry J. Wiegand, of Milwaukee, Wisconsin, for an improvement in "Resistance Units," errors appear in the printed specification requiring correction as follows: Page 1, line 95, and page 2, line 106, for the word "reflected" read *reflexed*; page 1, second column, second occurrence, for the line-indicating numeral "65" read 85; and that the said Letters Patent should be read with these corrections therein that the same may conform to the record of the case in the Patent Office.

Signed and sealed this 2nd day of February, A. D., 1915.

[SEAL.]

R. F. WHITEHEAD,

Acting Commissioner of Patents.
